SAFETY DEVICE FOR DRILLING DERRICKS

George E. Kemnitz, Tulsa, Okla., assignor to
 Noble Drilling Corp., Tulsa, Okla., a corpora-
 tion of Delaware

Application March 10, 1950, Serial No. 148,906

11 Claims. (Cl. 254—1)

1

The present invention relates to drilling derricks or masts, and more particularly to safety means capable of attachment to the legs of conventional drilling derricks or masts to prevent injury to members of a drilling crew by a joint of drill pipe or casing falling while it is being hoisted above the derrick floor from the pipe rack.

In oil well drilling or similar drilling operations, the derrick is positioned above the rotary table located at the center of the floor and pipe lengths are hoisted above the level of the floor through a door frame in the derrick or tower from a rack outside the derrick and below the level of the derrick floor, being pulled up a ramp during hoisting. Frequently during hoisting the hoisting cable will break while the pipe lengths are suspended therefrom and permit them to fall onto the floor and injure or kill members of the drill crew on the floor. Principal objects and features of this invention are the provision of simple safety means or safeguards designed to prevent such injuries or death by trapping the pipe lengths in their fall on breakage of the hoisting line and precluding their falling to the floor of the derrick.

Further principal objects and features of the invention are the provision of safety means of the character described that are simple in construction, relatively inexpensive and capable of being installed on existing structures without any material modification of the latter.

Other objects and novel features will become apparent from the following specification and accompanying drawings, wherein similar reference characters denote corresponding parts and wherein:

Fig. 1 is a vertical elevation, partially in section, of a conventional drilling derrick equipped with the safety means of the invention;

Fig. 2 is a transverse section taken along line 2—2 of Fig. 1 and viewed in the direction of the arrows;

Fig. 3 is an elevational view of the derrick of Fig. 1 viewed from the right of Fig. 1 and showing one position of the drill pipe being hoisted above the derrick floor;

Fig. 4 is a similar elevational view showing another position of the drill pipe being hoisted and in relationship to the safety means;

Fig. 5 is an enlarged fragmentary elevation illustrating details of construction of the safety means;

Fig. 6 is a transverse section taken along line 6—6 of Fig. 5 and viewed in the direction of the arrows; and

2

Fig. 7 is a broken section taken along line 7—7 of Fig. 5 and also viewed in the direction of the arrows.

Referring to the drawing, the drilling derrick or mast 10 is positioned above the rotary table 11 located at the center of the derrick floor 12. At one side of the derrick floor 12 is the conventional draw works 13 from which the drilling line 14 runs up through the crown block (not shown) and to traveling blocks (not shown) supporting the hook (not shown) and elevators. At one end of the draw works is a winch or cathead 15. Opposite the draw works on the opposite side of the derrick or tower 10 is the entrance frame or V-door 16 through which additional drill pipe or casing lengths 17 are brought and hoisted above the floor 12 as needed. The pipe or casing lengths 17 are usually racked outside the derrick on a lower level than the derrick floor 12 and are pulled up a ramp or walkway 18 by attaching a sling line 19 to the section or length 17 to be moved from the rack to a position above the floor 12. The sling line 19 is run through the crown block (not shown) and the other end is wound around the winch or cathead 15 which is motivated by the draw works 13. Sometimes the sling line 19 will break as the pipe length 17 is being hoisted above the derrick floor 12 as described and the pipe length will fall or drop to the derrick floor where it may strike and severely injure or kill a member of the drilling crew.

The safety means embodying the invention has as its principal object the provision of a trapping arrangement that will absolutely prevent any injury to the drill crew in the event of breakage of a sling line during the hoisting operations just described. To this end, one bracket 20 of a pair of brackets having a hooked flange 20a is secured by a clamp plate 21 and bolts 22 and nuts 23 to one of the frame legs 25 of the frame or V-door 16 adjacent its lower end. A similar bracket 20 is similarly secured to the other frame leg 25 of the frame or V-door 16. Each bracket 20 has a pivot shaft 26 fixed to and extending laterally thereof and outwardly of the V-door. A lever arm 27 is rotatably supported on each shaft 26 being located and held in place rotatively thereon by washers 28, 29 and a cotter pin 30. Each lever 27 fits telescopically in one end of a tubular arm 31. The latter is secured to the lever on which it fits by a collar 32 and cross bolt 33. The two arms 31 are oppositely directed toward each other and their adjacent outer ends 31a are preferably closed by plugs 34 whose 55 meeting outer surfaces are angularly shaped in

complementary manner so that the two angular surfaces of the plugs meet and permit the two adjacent ends of arms 31 to form a substantially closed inverted V in their lowermost positions. A cable securing sleeve 35 carrying a cable securing loop 36 is mounted on each pipe 31. A cable coupler 37 is secured to each loop 36 and a cable of wire or rope 38 in turn has one end secured to each coupler 37. The other ends of cables 38 are each secured to a coupler 39 and each latter coupler is secured to a fixed ring 40, each ring 40, in turn, being fixedly mounted to one of the frame legs 25 of the frame or V-door 16 above the clamp plate 21 on that leg. The two cables 38 serve to limit downward rotation of the two arms 31 to their lowermost positions shown in Figs. 3, 4 and 5, wherein their ends meet without, however, interfering with upward rotation of the two arms on their pivot shafts 26.

These two arms 31 supported as described in the frame or V-door 16 and their cables 38 provide a very effective safety means for drill crew members on the floor 12 of the derrick. As the winch 15 is operated to draw sling line 19 in a hoisting direction of a pipe length 17, the latter is drawn up the ramp 18 and through the frame or V-door 16. In the hoisting travel of the pipe length 17, its surface engages the undersides of arms 31 adjacent the outer ends 31a and pivots each arm about its shaft 26 to permit separation of the ends 31a sufficiently for the pipe length 17 to pass between the separated ends to the upper side of pipes 31 whereupon the latter immediately fall by gravity to their cable limited lowermost positions, closing the gap between adjacent ends 31a of the arms. This occurs early in the hoisting operation. Any subsequent breaking of the sling line during hoisting of the pipe length 17, since the latter is at an angle to the vertical, simply allows the pipe length to fall onto the top sides of the arms 31 or cables 38. These arms 31 or cables 38 thus form a trap, blocking a fall of the pipe length 17 onto the floor of derrick 12 because of their described return to meeting position immediately after pipe is drawn through the gap between the arms and thereby protect the drilling crew below on the derrick floor 12 against injury or death.

The arrangement while very simple in practice has proved very effective in the field as a crew safety device. Its ready installation on existing structures adds greatly to its commercial utility and, when installed, reduces one of the causes of large accident rates in drilling operations.

While a specific embodiment of the invention has been described and shown, variations in structural detail within the scope of the claims is possible and is contemplated. There is no intention, therefore, of limitation to the exact details shown and described.

What is claimed is:

1. In a drilling derrick having an entrance frame and means for hoisting a pipe length through the frame and above the floor of the derrick, safety means comprising a pair of oppositely directed arms each pivotally supported at one of its ends at opposite sides of the frame and normally having their free ends meeting, means for preventing pivotal movement downwardly of the two arms substantially below the meeting position of their free ends while permitting upward pivotal movement of the arms to provide temporary separation of the free ends thereof during passage in upward direction therebetween of a pipe length being hoisted, said arms

being free to return under the influence of gravity to meeting relationship of their said free ends thereby providing a trap above the derrick floor to prevent the length of pipe being hoisted from falling onto the floor.

2. In hoisting apparatus for lifting pipe lengths through an entrance frame and over a floor, safety means comprising a pair of oppositely directed arms each pivotally supported at one of its ends at opposite sides of the frame and normally having their free ends meeting, means for preventing pivotal movement downwardly of the two arms substantially below the meeting position of their free ends while permitting upward pivotal movement of the arms to provide temporary separation of the free ends thereof during passage in upward direction therebetween of a pipe length being hoisted, said arms being free to return under the influence of gravity to meeting relationship of their said free ends thereby providing a trap above the derrick floor to prevent the length of pipe being hoisted from falling onto the floor.

3. The safety means of claim 2, wherein brackets are secured to the frame, each bracket having a pivot stud, and wherein levers are rotatively mounted one on each pivot stud and wherein the arms fit telescopically one on each lever and are secured thereto.

4. The safety means of claim 2, wherein brackets and clamp plates for securing the brackets to the frame are provided, a pivot stud on each bracket and levers rotatively mounted one on each pivot stud, wherein the arms are tubular and fit telescopically one on each lever and wherein means for securing each arm to the lever on which it fits are provided.

5. The safety means of claim 2, wherein the means for limiting downward pivotal movement of the two arms includes a cable of determined length connected to each arm and to the frame.

6. Safety means for application to the frame of a drilling derrick, wherein pipe lengths are hoisted through the frame and above the derrick floor comprising a pair of oppositely directed arms each pivotally supported at one of its ends at opposite sides of the frame above the floor and normally having their free ends meeting, means for preventing pivotal movement downwardly of the two arms substantially below the meeting position of their free ends while permitting upward pivotal movement of the arms to provide temporary separation of the free ends thereof during passage upwardly therebetween of a pipe length being hoisted, said arms being free to return under the influence of gravity to meeting relationship of their free ends, thereby providing a trap above the floor to catch and prevent the pipe length being hoisted from falling onto the floor.

7. The safety means of claim 6, wherein the arms in the meeting position of their free ends define a closed substantially inverted V.

8. The safety means of claim 6, wherein the means for limiting downward pivotal movement of the two arms comprise cables secured both to the arms and to the frame.

9. The safety means of claim 6, wherein each arm is tubular and fits telescopically on a lever and is secured thereto, brackets secured to the frame, and pivot studs secured to the brackets, each lever being pivotally mounted on one of the pivot studs.

10. The safety means of claim 6, wherein each arm is tubular and fits telescopically on a lever

75

and is secured thereto, brackets secured to the frame, and pivot studs secured to the brackets, each lever being pivotally mounted on one of the pivot studs and wherein the means for limiting downward pivotal movement of the two arms comprise cables secured both to the arms and to the frame, and wherein the arms in the meeting position of their adjacent ends define a closed substantially inverted V.

11. In combination with a drilling derrick having a V-door structure and means for hoisting a pipe length through the door and over the floor of the derrick, safety means comprising a pair of oppositely directed arms, means for pivotally supporting one end of each arm from one of the opposite sides of the structure forming the V-door, and means for preventing pivotal movement in a downward direction of at least one of said arms below that position at which the free

ends of the arms meet, said last-named means permitting pivotal movement of said arm in an upward direction to permit temporary separation of the free ends of the arms during passage in an upward direction between them of a pipe length being hoisted, said arms thereby providing a trap to prevent the pipe length being hoisted from falling onto the derrick floor.
